DISPENSING DEVICE

Emile Piquerez, Saint-Cloud, France

Application December 22, 1937, Serial No. 181,219
In France January 4, 1937

13 Claims. (Cl. 231—74)

The present invention aims at the provision of an apparatus, preferably portable, that will permit any desired quantity of the contents of a flexible package containing a liquid or viscous substance such as oil or grease to be supplied almost instantaneously and without soiling the hands.

According to one form of the invention the apparatus comprises, in combination, an outer casing intended to receive with some clearance a crushable package containing the substance to be supplied; means for permitting outflow from the casing of substance contained therein; means for forming a substantially sealed joint between an inserted package and said casing around said outflow means; a perforating nozzle element, slidably mounted in said casing, adapted to pierce the wall of the package and thereupon to provide communication between the interior of said package and the outflow means of the casing; and means for connecting said casing to a supply of fluid under pressure so that said fluid will enter between the wall of the casing and the package for the purpose of crushing the latter and discharging its contents.

The means for introducing the supply of compressed fluid under pressure to said casing preferably include a control device whereby the supply of such fluid can be started and stopped as required.

According to one particularly simple constructional embodiment use is made of a hollow perforator fixed to the end of a movable outlet tube that can slide in a fixed tube on the cover so that the perforator can be forced inwardly to pierce the end of a package in the casing. The movable tube is preferably provided with a return spring whilst at the base of said fixed tube is preferably provided a housing adapted to contain the perforator when at rest. In this case the side of the perforator adjacent to the movable tube on which it is fixed is further formed to provide a shoulder or rim, preferably of a diameter substantially equal to that of the housing of the perforator, so that when the perforator rises under the action of its return spring after having pierced the end of the package the said shoulder engages the edge of the opening thus formed and presses it against the rim of the housing in the cover so that leakage of the contents of the package between the fixed tube and the movable tube is prevented.

Further, according to one constructional example, when the package has a circular end, the casing and its cover are fastened together by se-

curing means comprising interengaging elements having inclined or helical surfaces adapted, upon relative rotation of said body and cover, to cause these parts to be clamped tightly together or released as required. The rim at the end of the flexible package may be arranged to be gripped between the body and cover, or a special jointing element may be provided.

The means employed for connecting the casing to a supply of compressed fluid may advantageously comprise two relatively movable, for example, rotatable parts. Thus, there may be a rotatable part forming part of a tubular handle and provided with passages capable of being brought into register with orifices in a fixed part which receives the ferrule of an air or other compressed fluid pipe.

The annexed drawings illustrate by way of example one constructional embodiment of an apparatus according to the invention.

Fig. 1 is a view in vertical section and partly in elevation, the perforator being shown at rest.

Fig. 2 is a section on an enlarged scale of part of the apparatus in the working position.

Fig. 3 is a vertical section of a rotary control valve connection for supplying compressed air.

Fig. 4 is an underneath plan view of the upper member of the valve.

Fig. 5 is a plan view of the lower member of said valve.

In the construction illustrated, the apparatus is designed to receive a collapsible package 10 in the form of a wallis corner, that is to say, a package having its walls converging from a circular end or base to a straight ridge parallel with said end or base. The apparatus comprises an outer rigid box or casing, 11, of a form appropriate to that of the package 10 and constructed to receive said package with an appropriate lateral clearance by inserting it from one end and with the bottom 10a of the said package resting in the mouth of the said casing.

The casing, 11, is provided with a cover 12 provided with manipulating wings 12a and lugs 12b which co-operate with helicoidal surfaces on brackets 13 rigid with the casing to enable the cover to be clamped in position or released by a rotary movement and thus form a rapid acting fastening system providing a high degree of tightness.

By means of this arrangement the peripheral rim 10b securing the wall to the bottom of the package 10 is clamped between the cover 12 and the upper rim of the casing 11. The joint thus formed ensures that the space 14 around the

package is closed and prevents any communication between this space and the outlet from the apparatus.

Said outlet is constituted by a fixed guide in the form of a tube 15 integral with the cover and a movable tube 16 able to slide in the tube 15. The tube 16 is rigid at its lower end with a hollow perforator element 17, for example of conical form, whose lateral surface presents orifices 18 communicating with the hollow interior and, consequently, with the outlet tube 16.

The side of the perforator element 17 adjacent to the foot of the tube 16 is of greater diameter than said tube and forms with respect thereto a shoulder 17a slidably fitting with a minimum of clearance in a chamber 19 formed by a recess in the lower part of the tube 15. A spring 20 is interposed between the extremity of the tube 15 and a flange 21 fixed on the tube 16, so that the shoulder 17a of the perforator 17 is normally held against the inner end of the chamber 19 and the said perforator is entirely withdrawn into said chamber.

The device for the introduction of compressed fluid to the casing 11 will now be described. For this purpose the casing 11 is provided, for example on its side, with a tube 22 on which is mounted a tubular handle 23. Said handle 23 and tube 22 are constructed to form a rotary distributor valve, for which purpose the extremity of the tube 22 is provided with a base member 24 traversed by passages 25, 26, adapted respectively to register with two other passages 27, 28 formed in a member 29 which forms the bottom 35 of the handle 23.

The two opposite faces of the upper and lower members 24 and 29 of the valve are carefully set and are maintained in contact with one another by the action of a spring 30 disposed in a housing 31 in the handle 23 between the bottom of said housing and the rim 24a of the member 24.

The passage 27 in the lower member 29 communicates with a connection 32 of any appropriate type adapted to be joined to a conduit 45 of air or other compressed fluid whilst the passage 28 communicates with the atmosphere by way of a small channel 33.

The two operating positions of the handle-valve are fixed by means of a spring finger 34, 50 arranged in the base member 29 and adapted to engage alternatively in two notches 35¹, 35², in the fixed member 24. When the apparatus is not in use, the finger 34 is engaged in the seating 35¹ and the passages 26, 28 are in communication, 55 the casing 11 being then at atmospheric pressure.

When the apparatus is required for use the package 10 is introduced into the casing 11 and the cover 12 (Fig. 1) is applied. The tube 16 is then pushed in briskly so that the perforator 17 60 perforates the end 10a of the package and said tube is let go. In returning under the action of the spring 10, the perforator engages by its shoulder 17a with the edge 36 of the opening which it has formed in the said end, so that this edge is urged upwardly and caused to bear 65 against the cover around the mouth of the chamber 19 (Fig. 2). The joint thus formed resists to the leakage of the contents of the package between the two tubes 15 and 16. In order to 70 discharge said contents, the apparatus is connected to a compressed air conduit and the handle 23 turned until the finger 34 engages in the other notch 35². (Fig. 3). In Fig. 3 of the drawings this finger 34 has been shown for 75 convenience in the radial plane of the passages

25, 27 when registered. The compressed air now has access to the interior of the casing 11 and causes the gradual crushing of the package 10 and, consequently, expulsion of the lubricant through the perforator 17 and tube 16. When the 5 desired quantity has been discharged the discharge is stopped simply by returning the handle 23 to its initial position, whereupon the connection 32 can be uncoupled from the air supply if desired.

It will be appreciated that the apparatus according to the invention will be extremely useful in practice and by virtue of its mobility will be of the greatest value in garages and service stations for automobiles, as well as for use in industrial establishments generally where, since there is no loss, it will permit the rapid and economical recharging of all hand greasing apparatus as well as the direct re-charging of greasers of large capacity.

It will be well understood that the invention is not restricted to the constructional embodiment described and illustrated, but includes any variations thereof coming within the scope of the appended claims.

Having described my invention herebefore, what I claim is:

1. Apparatus for supplying liquids or viscous and like substances comprising, in combination, a casing having, at least, one open end; a crushable package in said casing for containing the substances to be supplied, the end of said package when introduced to its full extent into the casing closing the said open end of the latter, and the body of the package lying with a clearance therein; a cover for closing the open end of said casing, said cover being provided with means forming an outlet for the contents of the package and being adapted when closed to produce a joint with the wall of said package around the outflow means; means for clamping the cover on the casing; a perforating nozzle mounted on the cover, adapted to pierce the wall of the package and thereupon to provide communication between the interior of said package and the outflow means of the casing; and means for introducing a supply of fluid under pressure to said casing between the wall thereof and the wall of the package for the purpose of crushing the latter and discharging its contents.

2. Apparatus for supplying liquids or viscous and like substances comprising, in combination, a casing having at least one open end; a crushable package in said casing for containing the substances to be supplied, the end of said package when introduced to its full extent into the casing closing the said open end of the latter, and the body of the package lying with a clearance therein, a cover for closing the open end of said casing; said cover being provided with means providing an outlet for the content of the package and being adapted when closed to produce a joint with the wall of said package around the outflow means; means for clamping the cover on the casing; a perforating nozzle mounted on the cover, adapted to pierce the wall of the package, said striker element being combined with the outflow means of the casing and providing communication between the interior of said package and said outflow means when the piercing has been effected; and means for introducing a supply of fluid under pressure to said casing between the wall thereof and the wall of the package, said means including a control device.

whereby the supply can be started and stopped as required.

3. Apparatus for supplying liquids or viscous and like substances comprising, in combination, 5 a casing having at least one open end; a crushable package in said casing for containing the substance to be supplied, the end of said package when introduced to its full extent into the casing closing the said open end of the latter and 10 the body of the package lying with a clearance therein; a cover for closing the open end of said casing, said cover having an outlet tube fixed thereon in which a further tube is slidably mounted and a hollow perforating element 15 mounted on the lower end of said slidable tube, said perforating element being adapted to pierce the end of the package when forced against it and having openings providing communication between the interior of said tube and the outer 20 face of the perforating element; resilient means acting to maintain said slidable tube normally in a raised position; and means for introducing a supply of fluid under pressure to said casing between the wall thereof and the wall of the package for the purpose of 25 crushing the latter and discharging its contents.

4. Apparatus for supplying liquids or viscous and like substances comprising, in combination, a casing having at least one open end; a crushable package in said casing for containing the substance to be supplied, the end of said package when introduced to its full extent into the casing closing the said open end of the latter and the body of the package lying with a clearance 30 therein; a cover for closing the open end of said casing, said cover having an outlet tube fixed thereon in which a further tube is slidably mounted, and being adapted when closed to produce a joint with the wall of said package around 35 said outlet tube, and said fixed tube presenting at its base a recess open to the interior of the cover; a hollow perforating element mounted on the lower end of said slidable tube, said perforating element being adapted to pierce the end of the package when forced against it and having 40 openings providing communication between the interior of said tube and the outer face of the perforating element; resilient means acting to maintain said slidable tube normally in a raised position in which the perforating element is disposed in the recess at the base of the fixed tube, so that perforation of the package can be effected 45 by pushing in said sliding tube against the action of said resilient means, the perforating element being in the form of a cone whose base is of greater diameter than the sliding tube on which it is fixed and is substantially equal to that of the cylindrical recess in the base of the fixed tube, so that when the perforating element returns under the action of its resilient means after piercing the package it engages the edge of the opening formed in said package and forces said edge 50 against the rim of the cylindrical recess; and means for introducing a supply of fluid under pressure to said casing between the wall thereof and the wall of the package for the purpose of 55 crushing the latter and discharging its contents.

5. Apparatus for supplying liquids or viscous and like substances comprising, in combination, 60 a casing having, at least, one open end; a crushable package in said casing for containing the substance to be supplied, the end of said package when introduced to its full extent into the casing closing the said open end of the latter, and the body of the package lying with a clearance 65 therein; a cover for closing the open end of said casing, said cover having an outlet tube fixed thereon in which a further tube is slidably mounted, and being adapted when closed to produce a joint with the wall of said package around 70 said outlet tube and said fixed tube presenting at its base a recess open to the interior of the cover; a hollow perforating element mounted on the lower end of said slidable tube, said perforat-

ing element being adapted to pierce the end of the package when forced against it and having openings providing communication between the interior of said tube and the outer face of the perforating element; resilient means acting to 5 maintain said slidable tube normally in a raised position in which the perforating element is disposed in the recess at the base of the fixed tube, so that perforation of the package can be effected by pushing in said sliding tube against the action of said resilient means; means for retaining the perforating element in the package after piercing has been effected; means for pressing against the cover the edge of the opening formed in the package by the perforating element; and means for introducing a supply of fluid under pressure to said casing between the wall thereof and the wall of the package for the purpose of 10 crushing the latter and discharging its contents. 15

6. Apparatus for supplying liquids or viscous and like substances comprising, in combination, a casing having at least one open end, a crushable package in said casing for containing the substance to be supplied, the end of said package when introduced to its full extent into the casing closing the said open end of the latter, and the body of the package lying with a clearance therein; a cover for closing the open end of said casing, said cover having an outlet tube fixed thereon in which a further tube is slidably mounted, and being adapted when closed to produce a joint with the wall of said package around said outlet tube, and said fixed tube presenting at its base a cylindrical recess open to the interior of the cover; a hollow perforating element mounted on the lower end of said slidable tube, said perforating element being adapted to pierce the end of the package when forced against it and having openings providing communication between the interior of said tube and the outer face of the 40 perforating element; resilient means acting to maintain said slidable tube normally in a raised position in which the perforating element is disposed in the recess at the base of the fixed tube, so that perforation of the package can be effected by pushing in said sliding tube against the action of said resilient means, the perforating element being in the form of a cone whose base is of greater diameter than the sliding tube on which it is fixed and is substantially equal to that of the cylindrical recess in the base of the fixed tube, so that when the perforating element returns under the action of its resilient means after piercing the package it engages the edge of the opening formed in said package and forces said edge 50 against the rim of the cylindrical recess; and means for introducing a supply of fluid under pressure to said casing between the wall thereof and the wall of the package for the purpose of 55 crushing the latter and discharging its contents. 60

7. Apparatus for supplying liquids or viscous and like substances comprising, in combination, a casing having at least one open end; a crushable package in said casing for containing the substance to be supplied, the end of said package when introduced to its full extent into the casing closing the said open end of the latter, and the body of the package lying with a clearance therein; a cover for closing the open end of said casing, said cover having an outlet tube fixed thereon in 65 which a further tube is slidably mounted, and being adapted when closed to produce a joint with the wall of said package around said outlet tube, said fixed tube presenting at its base a cylindrical recess open to the interior of the cover; 70

means for clamping the cover on the casing comprising relatively inclined surfaces on parts of the cover and casing respectively adapted upon relative rotation of said body or cover to cause these parts to be clamped tightly together or released as required; a hollow perforating element mounted on the lower end of said slideable tube, said perforating element being adapted to pierce the end of the package when forced against it and having openings providing communication between the interior of said tube and the outer face of the perforating element, so that perforation of the package can be effected by pushing in said slide tube against the action of said resilient means, the perforating element being in the form of a cone whose base is of greater diameter than the slide tube on which it is fixed and is substantially equal to that of the cylindrical recess in the base of the fixed tube, so that when the perforating element returns under the action of its resilient means after piercing the package it engages the edge of the opening formed in said package and forces said edge against the rim of the cylindrical recess; and means for introducing a supply of fluid under pressure to said casing between the wall thereof and the wall of the package, said means including a control device whereby the supply can be started and stopped as required.

30 8. Apparatus for supplying liquids or viscous and like substances comprising, in combination, a casing having at least one open end, a crushable package in said casing for containing the substance to be supplied, the end of said package when introduced to its full extent into the casing closing the said open end of the latter, and the body of the package lying with a clearance therein; a cover for closing the open end of said casing, said cover having an outlet tube fixed thereon in which a further tube is slideably mounted, and being adapted when closed to produce a joint with the wall of said package around said outlet tube, said fixed tube presenting at its base a cylindrical recess open to the interior of the cover; means for clamping the cover on the casing comprising relatively inclined surfaces on parts of the cover and casing respectively adapted upon relative rotation of said body or cover to cause these parts to be clamped tightly together or released as required; a hollow perforating element mounted on the lower end of said slideable tube, said perforating element being adapted to pierce the end of the package when forced against it and having openings providing communication between the interior of said tube and the outer face of the perforating element; resilient means acting to maintain said slideable tube normally in a raised position in which the perforating element is disposed in the recess at the base of the fixed tube, so that perforation of the package can be effected by pushing in said slide tube against the action of said resilient means; the perforating element being in the form of a cone whose base is of greater diameter than the slide tube on which it is fixed and is substantially equal to that of the cylindrical recess in the base of the fixed tube, so that when the perforating element returns under the action of its resilient means after piercing the package it engages the edge of the opening formed in said package and forces said edge against the rim of the cylindrical recess; and means for introducing a supply of fluid under pressure to said casing between the wall thereof and the wall of the package, said means comprising a supply connection to the casing and two

relatively rotatable elements ported to form valve members adapted on relative rotation to open or cut off the supply as required, one of said parts forming a handle and the other being connected to a compressed fluid conduit. 5

9. Apparatus for supplying liquids or viscous and like substances comprising, in combination, a casing having at least one open end; a crushable package in said casing for containing the substance to be supplied, the end of said package when introduced to its full extent into the casing closing the said open end of the latter, and the body of the package lying with a clearance therein; a cover for closing the open end of said casing, said cover having an outlet tube fixed thereon in which a further tube is slideably mounted, and being adapted when closed to produce a joint with the wall of said package around said outlet tube, and means for clamping the cover on the casing; said fixed tube presenting at its base a recess open to the interior of the cover; a hollow perforating element mounted on the lower end of said slideable tube, said perforating element being adapted to pierce the wall of the package when forced against it and having openings providing communication between the interior of said tube and the outer face of the perforating element; resilient means acting to maintain said slideable tube normally in a raised position in which the perforating element is disposed in the recess at the base of the fixed tube, so that perforation of the package can be effected by pushing in said slide tube against the action of said resilient means; means for retaining the perforating element in the package after piercing has been effected; means for pressing against the cover the edge of the opening formed in the package by the perforating element; and means for introducing a supply of fluid under pressure to said casing between the wall thereof and the wall of the package, said means comprising a supply connection to the casing and two relatively rotatable elements ported to form valve members adapted on relative rotation to open or cut off the supply as required, one of said parts forming a handle and the other being connected to a compressed fluid conduit. 25

10. Apparatus for supplying liquids or viscous or like substances comprising, in combination, a casing having at least one open end; a crushable package in said casing for containing the substance to be supplied, the end of said package when introduced to its full extent into the casing closing the said open end of the latter, and the body of the package lying with a clearance therein; a cover for closing the open end of said casing, said cover having an outlet tube fixed thereon in which a further tube is slideably mounted, and being adapted when closed to produce a joint with the wall of said package around said outlet tube, and said fixed tube presenting at its base a cylindrical recess open to the interior of the cover; a hollow perforating element mounted on the lower end of said slideable tube, said perforating element being adapted to pierce the end of the package when forced against it and having openings providing communication between the interior of said tube and the outer face of the perforating element; resilient means acting to maintain said slideable tube in a raised position in which the perforating element is disposed in the recess at the base of the fixed tube, so that perforation of the package can be effected by pushing in said slide tube against the action of said resilient means; the perforating element 30

being in the form of a cone whose base is of greater diameter than the sliding tube on which it is fixed and is substantially equal to that of the cylindrical recess in the base of the fixed tube, so when the perforating element returns under the action of its resilient means after piercing the package it engages the edge of the opening formed in said package and forces said edge against the rim of the cylindrical recess; and means for introducing a supply of fluid under pressure to said casing between the wall thereof and the wall of the package, said means comprising a supply connection to the casing and two relatively rotatable elements ported to form valve members adapted on relative rotation to open or cut off the supply as required, one of said parts forming a handle and the other being connected to a compressed fluid conduit.

11. Apparatus for supplying liquids or viscous and like substances comprising, in combination, a casing having at least one open end; a crushable package in said casing for containing the substance to be supplied, the end of said package when introduced to its full extent into the casing closing the said open end of the latter, and the body of the package lying with a clearance therein; a cover for closing the open end of said casing, said cover being provided with means providing an outlet from the casing for the content of the package and being adapted when closed to produce a joint with the wall of said package around the outflow means; means for clamping the cover on the casing comprising relatively inclined surfaces on parts of the cover and casing respectively adapted upon relative rotation of said body or cover to cause these parts to be clamped tightly together or released as required; a perforating element mounted on the cover, adapted to pierce the wall of the package, said perforating element being combined with the outflow means of the casing and providing communication between the interior of said package and said outflow means when the piercing has been effected; and means for introducing a supply of fluid under pressure to said casing between the wall thereof and the wall of the package, said means comprising a supply connection to the casing and two relatively rotatable

elements ported to form valve members adapted on relative rotation to open or cut off the supply as required, one of said parts forming a handle and the other being connected to a compressed fluid conduit.

12. Apparatus for supplying liquids or viscous and like substances comprising, in combination, a casing having at least one open end, said casing being intended to receive a crushable package containing the substance to be supplied, which package when introduced to its full extent into the casing will close the open end of the latter and lie therein with a clearance; a cover for closing the open end of said casing, said cover being provided with means providing an outlet from the casing for the content of the package and being adapted when closed to produce a joint with the wall of an inserted package around the outflow means; means for clamping the cover on the casing; a perforating element, mounted on the cover, adapted to pierce the wall of an inserted package and thereupon to provide communication between the interior of said package and the outflow means of the casing; and means for connecting said casing to a supply of fluid under pressure so that said fluid will enter between the wall of the casing and the package for the purpose of crushing the latter and discharging its contents.

13. Apparatus for supplying liquids or viscous and like substances comprising, in combination, an outer casing intended to receive with some clearance a crushable package containing the substance to be supplied, means providing an outlet from the casing for substances contained therein; means for forming a substantially sealed joint between an inserted package and said casing around said outflow means; a perforating element, mounted in said casing, adapted to pierce the wall of the package and thereupon to provide communication between the interior of said package and the outflow means of the casing; and means for connecting said casing to a supply of fluid under pressure so that said fluid will enter between the wall of the casing and the package for the purpose of crushing the latter and discharging its contents.

EMILE PIQUEREZ.
